No. 691,390.

Patented Jan. 21, 1902.

T. F. KENNEY.

HORSESHOE.

(Application filed May 11, 1901.)

(No Model.)

UNITED STATES PATENT OFFICE.

THOMAS F. KENNEY, OF LA CROSSE, WISCONSIN, ASSIGNOR OF ONE-HALF TO
HERMAN C. SCHARPF AND FRANK G. ROTH, OF LA CROSSE, WISCONSIN.

HORSESHOE.

SPECIFICATION forming part of Letters Patent No. 691,390, dated January 21, 1902.

Application filed May 11, 1901. Serial No. 59,835. (No model.)

To all whom it may concern:

Be it known that I, THOMAS F. KENNEY, a citizen of the United States, residing at La Crosse, in the county of La Crosse and State of 5 Wisconsin, have invented certain new and useful Improvements in Horseshoes; and I do hereby declare the following to be a full, clear, and exact description of the invention, such as will enable others skilled in the art 10 to which it appertains to make and use the same.

Horseshoes of solid metal are trying on animals compelled to travel on cobblestone roads and hard and unyielding surfaces of 15 concrete, Belgian block, and kindred hard pavements, producing lameness and soreness and otherwise affecting their efficiency. To minimize the jar to the limbs incident to the impact of the foot with the stone-like surface, 20 cushioning devices are provided and interposed between the shoe and the foot or applied to the tread side of the shoe.

This invention relates to the class of shoes having a soft-tread side formed by rubber or 25 flexible material attached thereto. The shoe may be of any form, pattern, or size and may be provided with or constructed without a heel-bar.

The invention will be more particularly set 30 forth hereinafter and claimed and is illustrated in the annexed drawings, in which—

Figure 1 is a bottom view of a horseshoe constructed in accordance with this invention. Fig. 2 is a perspective view of the 35 lower side of the shoe, the packing being removed. Fig. 3 is a transverse section of the complete shoe. Fig. 4 is a longitudinal section thereof. Fig. 5 is a perspective view of a modification, parts being broken away.

40 Corresponding and like parts are referred to in the following description and indicated in all the views of the drawings by the same reference characters.

While the shoe illustrated is provided with 45 a heel-bar, it is to be understood that the shoe may be of any type and that the provision of the heel-bar is not essential to the spirit of the invention. The shoe proper may be of metal or fiber or of any desired material and may be of any size, pattern, or make. 50 Of the metals aluminium is preferred, because

of its lightness and strength. The lower or tread side of the shoe is formed with a channel, groove, or recess 1, forming an inner wall 2 and outer wall 3. This depression or 55 groove 1 extends entirely around the shoe and receives the anchoring-rib 4 of the cushion or soft-tread material 5, applied to the lower or tread side of the shoe. The walls of the depression or groove 1 are undercut, and 60 the edges of the rib 4 are correspondingly beveled, so as to engage under the oppositely inclined walls of the depression 1 and securely hold the cushion 5 in place. An intermediate portion of the side members of 65 the outer wall 3 is widened, as shown at 6, and receives the usual crease and nail-openings. This widened part 6 contracts the depression 1, and the side portions of the cushion or soft tread 5 are cut away, so as to provide ample clearance for the nail-openings and connecting-crease, thereby enabling the shoe to be nailed without interference of the cushion with the nails or operation.

The cushion or soft tread 5 approximates 75 the form of the horseshoe and is secured thereto preferably by the anchoring-rib 4, which fills the anchoring-groove 1. This cushion or soft-tread material may be molded, pressed, or otherwise applied to the lower side 80 of the shoe. Its heel and toe portions extend the full width of the shoe, thereby providing a maximum amount of material for relieving the limb of jar and jolt. The outer edge portions are cut away opposite the widened parts 85 6 of the outer wall 3, so as to clear the nail-openings and crease. The heel and toe portions of the cushion or soft tread are thickened to provide heel-calks 7 and a toe-calk 8, thereby increasing the cushioning action of 90 the soft tread and adding to the life thereof.

To increase the connection between the shoe and the cushion, so as to prevent the latter from stripping, it is proposed to provide the shoe with headed studs 9, which are by preference located in the groove or channel 1 at the toe and heel portions, since these parts are subjected to the greatest strain. It is also proposed to provide a series of openings 10 in the outer wall 3 of the shoe, and these openings are arranged at the heel and toe of the 100 shoe for the same reason assigned for placing

the studs 9 at the points indicated. The rubber, fibrous material, or cushion forming the soft tread passes through openings 10 and around the shanks and beneath the heads of 5 the studs 9, thereby adding materially to the strength of the joint between the cushion and the body of the shoe.

Having thus described the invention, what is claimed as new is—

- 10 1. A horseshoe having a depression or groove in its lower or tread side forming inner and outer walls, the outer wall being widened intermediate of the ends of the side members of the shoe and provided with the usual nail-openings and crease, the walls of the depression being undercut, and a cushion or soft tread applied to the lower side of the shoe and having an anchoring-rib filling the depression or groove thereof and having the 15 outer edge of its side members cut away opposite the widened outer wall of the shoe so as to clear the nail-openings and crease and having the heel and toe portions thickened to provide calks, substantially as set forth.
- 20 2. A horseshoe provided with a heel-bar and having a groove or depression in the tread side throughout the extent of the shoe and heel-bar and having the walls of the depres-

50 sion undercut and having the intermediate portion of the outer wall widened and formed with nail-openings and creases, and a cushion or soft tread covering the lower side and heel-bar of the shoe and having an anchoring-rib filling the depression thereof, said cushion being cut away or reduced in width opposite the widened portions of the outer wall of the shoe to expose the nail-openings and creases and having its heel and toe portions thickened to provide calks, substantially as specified.

40 3. A horseshoe having a groove or depression in its tread side and extending throughout the extent of the shoe and having headed studs within said groove and having a series of openings in the part of the shoe exterior to said groove, and a cushion or soft tread fitted to the lower side of the shoe and filling the openings and groove thereof and embracing the shank portions of the headed studs, substantially as set forth.

45 In testimony whereof I affix my signature in presence of two witnesses.

50 THOMAS F. KENNEY. [L. S.]
